United States Patent Office.

JULIUS SHELDON, OF NEW YORK, N. Y., ASSIGNOR TO HIMSELF AND
W. C. GRISWOLD, OF SAME PLACE.

Letters Patent No. 63,109, dated March 19, 1867.

IMPROVEMENT IN HAT-BLOCKING MACHINES.

The Schedule referred to in these Letters Patent and making part of the same.

Be it known that I, JULIUS SHELDON, of the city, county, and State of New York, have invented new and useful Improvements in Hat-Blocking Machines, and that the following is a full and clear description thereof, reference being had to the annexed drawings, of which—

Figure 1 is a vertical section of the machine in such a position as it requires to be before the operation of blocking a hat-body commences.

Figure 2 is also a vertical section of the machine, showing the various parts in the position in which they will be when the hat-body is blocked or stretched to the shape required.

Figure 3 is a plan view of the machine in the position shown in fig. 2, showing only two of the clamps.

Figure 4 represents the lower side of the plate.

My improvements consist in arranging the various parts of the hat-blocking machine patented to Joseph De Lamar, so as to make them adjustable in regard to size and depth so that every size and depth of hat can be made on each machine, and also in the apparatus for giving the proper pressure to the clamps, which perform the stretching of the brim of the hat, and in the mechanism for opening and closing said clamps.

Referring to the drawings, *a* is a square table, in the centre of which there is a hollow vertical stem, *b*, through the centre of which runs a rod, *c*, which bears at its upper extremity a round hub, *d*, to which are hinged a number of arms, *e*. Each of these arms is hinged to the upper end of a vertical bar, *f*, which has a stationary but adjustable fulcrum at *g*, below the plate *h*, to which the clamps *i* are jointed. These bars *f* perform the stretching of the crown by expanding, as shown in the drawings, the hat-body being held at the place where the band of the hat requires to be by a ring, *k*, which determines the size of the hat. The fulcrum *g*, on which the bars *f* turn, consists of a pin inserted in the slotted pieces *l*, and these pieces *l* slide in guides, *m*, and can be shifted in and out, to suit the size of the hat required, by a cone, *n*, which turns on a screw cut on the hollow stem *b*. In order to adjust these bars *f* to the depth of the hat the lower part of these bars is provided with notches, *g'*, about $(\frac{1}{4})$ one-fourth of an inch distant from each other, serving as seats for the fulcrum pins *g*, so that when the bars are all placed so that the upper notches engage the fulcrum pins the lowest hat can be made on the machine, and when they are placed so that the lowest notches engage the fulcrum pins the tallest hat can be made. There is an elastic ring, *o*, placed all round these bars *f*, right below the plate *h* and opposite the fulcrum, for the purpose of keeping the notches in gear with their fulcrum pins. The ring *k*, which breaks the band, is provided with an India-rubber cushion, *j*, all round its periphery, wide enough to press upon the clamps *i*, when ring *k* is brought down upon the hat-body, and to keep up this pressure while the clamps are being raised to a horizontal position. The outer parts *i'* of the clamps *i* are provided with short arms, *i''*, by which all the clamps can be closed simultaneously by means of a ring, *p*, which receives an upward motion by levers, *p'*, comes in contact with the arms *i''*, closes the clamps, and holds them so until the ring *k* is brought down upon them. In order to open all the clamps simultaneously when the hat-body is to be removed the arms *i''* of the outer jaws of the clamps may be provided with counter-weights, *q*, or the outer jaw may be thrown out by a spring attached to the inner jaw.

The operation of the machine is as follows: The hat-body is placed over the machine; the ring *p* is raised, which closes the clamps; then the ring *k* is brought down upon the hat-body, and its cushion gives pressure to the clamps. Now the clamps can be raised, thereby bringing out the brim flat; and at last the crown can be stretched.

I am aware of the application of Joseph De Lamar, filed November 2, 1866, and hereby disclaim all the features of his invention; but what I claim as new, and as improvements upon the invention above referred to, and desire to secure by Letters Patent, is—

1. The bars *f*, provided with notches *g'* for the purpose of adjusting said bars to all depths of hats, substantially as described.
2. I claim the slides *l*, provided at one end with pins *g*, which act as the fulcrums of bars *f*, and having their inner ends so arranged with the cone *n* as to be adjustable, substantially as described.
3. The ring *k*, provided with a surrounding elastic cushion to adapt it to the two functions of breaking the band and giving the pressure to the clamps, substantially as described.
4. I claim the ring *p*, disconnected from but arranged to operate the clamps *i*, substantially as and for the purpose specified.

JULIUS SHELDON.
